UNITED STATES PATENT OFFICE.

RASMUS M. HVID, OF CHICAGO, ILLINOIS, ASSIGNOR TO R. M. HVID COMPANY, OF CHICAGO, ILLINOIS, A CORPORATION OF MICHIGAN.

LIQUID-FUEL FEED.

1,283,197.

Specification of Letters Patent. Patented Oct. 29, 1918.

Application filed December 3, 1917. Serial No. 205,133.

To all whom it may concern:

Be it known that I, RASMUS M. HVID, a citizen of the United States, and resident of Chicago, in the county of Cook and State 5 of Illinois, have invented certain new and useful Improvements in Liquid-Fuel Feeds, of which the following is a specification.

My invention relates to internal combustion engines and particularly to fuel feeding 10 means for engines of the type in which liquid fuel is fed in an uncarbureted condition directly to the cylinder.

In engines of the Hvid type, that is, in 15 which ignition is effected by the heat of compression and the charge is inhaled during the suction cycle, the fuel is supplied to the cylinder in liquid form, no means for carburation being employed. A valve is used for controlling the admission of the liquid 20 fuel and as the amount of fuel required for each charge is minute, the valve and the entrance opening for the fuel are necessarily quite small. Furthermore, in view of the high compression employed the valve must 25 seat with great accuracy. Therefore the smallest particle of solid matter which may lodge between the valve and its seat, serves to permit the escape of pressure from the compression space, which is exerted in the 30 liquid fuel supply pipe. The high pressure developed will eject the fuel in the pipe, and in the constructions heretofore employed the engine was stopped; this for the reason that the fuel was supplied by means of a 35 single pipe extending from the container to a manifold which served the plurality of cylinders. It is not entirely practical to employ a check-valve in the line, for the reason that the foreign matter can best be dislodged 40 by permitting the pressure to blow past the seat.

I have therefore devised a system of fuel supply so arranged that the main oil container, which may be of large capacity, is 45 located at a convenient point, say at the base of the engine, and an auxiliary container of small capacity is located at a convenient point above the cylinders. A pump for delivering oil from the main to the auxiliary 50 container, combined with an overflow pipe for maintaining a constant level in the auxiliary tank, serves to provide for the supply. In order to avoid the objections heretofore referred to, I provide a separate 55 conduit from the auxiliary container to each of

the cylinders. As the auxiliary container is in communication with the atmosphere, if any of the needle valves or fuel intake valves become clogged by foreign matter, the compressed air and fluid in that cylinder will 60 blow through the fuel feeding opening and the independent supply pipe, thence out through the vent in the auxiliary container. This will serve to clear the passage but will not affect in any manner the operation of 65 the remaining cylinders. This would not be possible if the fuel were supplied through a manifold.

The invention will be more readily understood by reference to the accompanying 70 drawings, wherein,

Figure 1 is a side elevation, partly dia- 75 grammatic in form, showing the applica-
tion of my improvement to a four-cylinder
engine, and,

Fig. 2 is an enlarged vertical section of 75
the feed valve which I employ.

In the drawings the engine cylinders are indicated at 10, four being shown. The engine may be of the type shown in the earlier 80
patents to Brons, Nos. 868,839 and 922,383,
while the valve construction, later to be
described, may conform to that shown in
the patent to Blakely, No. 1,245,312. It
will be understood that in an engine of this 85
type ignition is effected by the heat of com-
pression and the fuel in liquid form is in-
haled on the suction stroke. By means of
the system illustrated I am enabled to store
the bulk of the fuel in a tank 11, an auto- 90
matic pump 12, serving to elevate the fuel
and discharge it into an auxiliary tank or
container 13, which may be conveniently
located at a point adjacent to and above the
cylinders. An overflow pipe 14, serves to 95
maintain a constant level in the auxiliary
container. In order to avoid the objections
heretofore referred to, I provide independ-
ent conduits 15, 16, 17, 18, from the auxiliary
container to each of the cylinders. These 100
conduits are provided with manually con-
trolled valves 19, which are employed only
for shutting off the supply when the engine
is not in operation. When in operating con-
dition the conduits are open and in com- 105
munication with a needle valve 20, which
controls the intake port 21. An intake valve
22, which is automatically opened and
closed by the operation of the engine, serves
to close the intake port 21. When the valve 110

22, is open the required amount of fuel, together with a small quantity of air, are drawn into the explosion cup 23. The needle valve can be threaded and provided 5 with a lateral arm 24, adapted to be connected to the governor, not shown.

Assuming that a particle of foreign matter becomes lodged between the face of the valve 22, and its seat, it will be seen that 10 the compression developed in the respective cylinder will escape through the intake port 21, past the needle valve and into the conduit 15. The fuel in the conduit will be blown out and the pressure will escape 15 through the vent 25, in the auxiliary tank. There will be no material increase in the pressure within the tank which would have the effect of forcing an excess of fuel through the remaining valves. Neither will 20 the discharge of fuel from the conduit 15, have any effect on the operation of the engine as to the remaining cylinders. If the foreign matter is not blown out at once, the engine will slow down due to the interruption 25 of the one cylinder, whereupon the governor will act to open the needle valves, thus giving a larger escape opening for the pressure in the dead cylinder. This will assist in blowing out the foreign matter. If, however, 30 the interruption continues, the offending valve may be removed and cleaned even without shutting down the engine, if desired. This is all made possible because of the conduit arrangement.

35 While I have shown the improvement as applied to a four cylinder engine, it will, of course, be understood that this constitutes no limitation. The improvement may be applied with equal facility to any multi-cylinder engine.

40 I claim:

1. In a multi-cylinder, hydro-carbon engine, of the type in which liquid fuel is fed directly to the cylinders, the combination 45 with the cylinders, of a liquid fuel tank and an independent conduit from the tank to each cylinder, substantially as described.

2. In a multi-cylinder engine of the type in which uncarbureted fuel is inhaled di-

rectly into the cylinders, the combination 50 with the cylinders, of a liquid fuel tank having communication with the atmosphere, and an independent conduit communicating directly between the tank and each cylinder, substantially as described. 55

3. In a multi-cylinder engine of the type in which liquid fuel is fed directly to the cylinders, the combination with the cylinders of a liquid fuel intake valve in each cylinder, a liquid fuel supply tank, and an independent conduit extending from said tank to each of said cylinders, the flow of fuel through said conduits being controlled by said intake valves, substantially as described. 65

4. A multi-cylinder engine of a type in which liquid fuel is fed directly to the cylinders, the combination with the cylinders and pistons, of an intake valve for each cylinder for controlling the entrance of liquid fuel, said valve being opened at the beginning of and during the suction stroke of the piston and remaining closed until the next succeeding suction stroke, a liquid fuel supply tank, and a separate conduit extending from said supply tank to each of said cylinders and controlled by one of said intake valves, substantially as described. 70 75

5. A fuel supply system for a multi-cylinder engine of the type in which liquid fuel is fed directly to the cylinders, the combination of cylinders, a main fuel supply tank, an auxiliary fuel supply tank, means for maintaining a constant level of fuel in said auxiliary tank, an intake valve in each cylinder for controlling the entrance of liquid fuel, said intake valve being adapted to be opened at the beginning of the suction stroke of the engine, and a separate pipe extending from said supply tank to each cylinder and controlled by one of said intake valves, substantially as described. 80 85 90

Signed at Chicago, Illinois, this 30th day of November, 1917.

RASMUS M. HVID.
